US0D1056970S

(12) **United States Design Patent** (10) Patent No.: **US D1,056,970 S**
(45) Date of Patent: ** Jan. 7, 2025

(54) **TRANSPORTABLE REFRIGERATED MEDICINE STORAGE DEVICE**

(71) Applicant: **Faizan Ahmed**, San Jose, CA (US)

(72) Inventor: **Faizan Ahmed**, San Jose, CA (US)

(**) Term: **15 Years**

(21) Appl. No.: **29/898,286**

(22) Filed: **Jul. 25, 2023**

(57) **CLAIM**

The ornamental design for a transportable refrigerated medicine storage device as shown and described.

DESCRIPTION

FIG. 1 is a perspective elevation view of a transportable refrigerated medicine storage device showing our new design;

FIG. 2 is a front view thereof;

FIG. 3 is a back view thereof;

FIG. 4 is top view thereof;

FIG. 5 is bottom view thereof;

FIG. 6 is a right-side view thereof; and,

FIG. 7 is a left-side view thereof.
